GARRISON BABCOCK, OF ROCHESTER, NEW YORK, ASSIGNEE, BY MESNE ASSIGNMENTS,
TO FREDERICK C. STEVENS, OF ATTICA, NEW YORK.

MULTIPLE-CONTACT RELAY.

1,133,786.

Specification of Letters Patent. Patented Mar. 30, 1915.

Application filed September 21, 1912. Serial No. 721,621.

To all whom it may concern:

Be it known that I, GARRISON BABCOCK, citizen of the United States, residing at Rochester, in the county of Monroe and State of New York, have invented certain new and useful Improvements in Multiple-Contact Relays, of which the following is a specification.

My invention relates to improvements in multiple-contact relays, and has for its object the provision of a relay device, which will combine a maximum efficiency, certainty of operation and extreme compactness, whereby a relatively large number of electrical circuits may be opened or closed simultaneously.

My invention is particularly applicable for use in automatic or semi-automatic telephone systems, wherein certain groups or units of contacts must be frequently made and broken under severe operating conditions.

My relay device in its several embodiments, heretofore produced is designed for use, and insures satisfactory service under the conditions mentioned.

Describing in a preliminary way the salient features of my improvements, the same consists of an actuating electro-magnet, or a plurality of such magnets acting together for the purpose of altering the electrical condition of associated paired contact springs, each pair forming one terminal of the controlled circuit. These springs are mounted closely together in paired relation upon edge, preferably staggered in two horizontal planes. The ends of the paired springs preferably are divergently bent, and beneath the diverging ends, there are respectively positioned the opposing circuit terminals, comprising partially flattened wires, which are similarly staggered in a common insulating mounting trip, actuated through the agency of the electro-magnet or magnets. Obviously, these circuit-terminals may normally be held in engagement or out of contact, depending upon the character of the circuits to be controlled, and the groups of springs and coacting terminals may be assembled in accordance with the desired number of contacts to be made or broken, since the compact edgewise and staggered mount-

ing permits of the assemblage of numerous terminals within a small compass. In the type of contact-making apparatus herein adopted, rubbing contacts are made between the terminals and springs, thereby avoiding the undue expense entailed in supplying platinum contact points. Furthermore, my improved relay avoids the closure of any circuits thereby through series contacts, since the circuit terminals are respectively brought directly into engagement with each other.

Further details of my improvements may be more readily explained, by making reference to the accompanying drawings, wherein:

Figure 1, is a view in side elevation of a circuit breaking relay device embodying my improvements. Fig. 2, is a similar view of a circuit making relay-device. Fig. 3, is an underside view and Fig. 3^b is a cross sectional view of the assembling strap for securing the springs, terminals and insulating mountings assembled within the relay. Fig. 4, is an end view partially broken away, of the relay device of Fig. 1. Fig. 5, is an end view of the relay device of Fig. 2. Fig. 6, is a fragmentary side view, Fig. 6^a is a fragmentary top view, and Fig. 6^b is a fragmentary end view; all upon an enlarged scale, showing two contact springs and their associated terminal. Fig. 7, shows a side and end view respectively of one of the intermediate insulating mounting blocks for the springs and coacting terminal. Fig. 1^a is a plan view of a five unit multiple contact relay incorporating my improvements. Fig. 2^a, is a side view, and Fig. 3^a, is an end view thereof. Figs. 4^a and 5^a respectively show side and end views of the adjacent and end blocks for mounting the springs and terminals, with fragmentary portions therein. Fig. 1^b, is a view in side elevation, and partially in section showing a single electro-magnet adapted for the actuation of my improved multiple contact relay. Fig. 2^b shows an extension pole-piece thereof in side and end elevations. Fig. 3^b, shows side and top elevations of the spacing-member and mounting screw for the electro-magnet. Fig. 4^b, is a side view of the single-magnet, multiple-contact relay embodying my improvements. Fig. 5^b is an enlarged detail of

one of the flattened wire terminals preferably employed in my relay. Fig. 6^b, is an enlarged detail partially broken away of one set of paired contact springs, and Fig. 7^b, 5 is a fragmentary section showing the mounting of a group of springs and contact terminals within a suitable insulating cement.

Throughout the several figures of the drawings, I have employed the same character of reference to indicate similar parts.

It will be observed that in the different types of relays thus far developed along the lines of my invention, that the general relation of the magnet or magnets, the 15 springs, the coacting terminals, and their actuating parts is substantially identical. In the type of circuit-breaking relay, of course, the action of the armature is reversed for the purpose of separating the normally 20 closed contacts thereof, while said contact parts may be more conveniently mounted beneath, instead of above the electro-magnets.

I will first explain my improvements as 25 embodied in the circuit-making relay of Figs. 2 and 5, and detail the differences appearing in the other relays, as in particular the preferred single-magnet relay, of Figs. 1^b and 4^b as representing the most efficient, 30 simple and compact type for many purposes. The magnet frame *a* supports the two electro-magnets *b* *b*, partially inclosed beneath said frame. The armatures *c* *c* are of the bell-crank type, and are united for 35 concerted action by the strap *d*. The longer arms of the bell-crank levers *c'* lie upon the top of the frame; being substantially co-extensive in length with the electro-magnets. The paired contact springs *e* and their co- 40 acting terminals *f* are rearwardly secured within the composite mounting strip; the former preferably being in staggered relation. Some thirty-one pairs of springs are shown in full size by Fig. 5 of the drawings. 45 These springs are of peculiar rectangular form, and are mounted upon edge with the rectangularly extending ends thereof, slightly flared or divergently bent, respectively to engage the coacting terminals. 50 Somewhat the same result of a staggered mounting for the springs, may be obtained by employing alternating paired springs having longer and shorter rectangular extensions, as indicated in Fig. 7^b. The coacting 55 terminals are also of distinctive construction, being formed of short lengths of wire flattened approximately throughout one-half to two-thirds of their lengths and rearwardly milled, or suitably roughened, as 60 are the springs, in order to hold these parts more securely within the composite mounting strip. These springs and terminals are capable of being very closely mounted adjacent to each other in the desired groups, 65 or substantially unitary structure, between

insulating fiber parts, such as shown in Figs. 4^a, 5^a and 7. The intermediate fiber insulators *i* (Fig. 7) have narrow grooves *i'* *i''* on either side substantially half the width of the flattened terminals *f*, and standard 70 shallower grooves *i'''* *i''''* within their side walls, substantially the thickness of one of the paired springs *e*, while the top is cut by a groove *i'''* for the accommodation of the mounting strip *j*. This strip is shown in 75 Fig. 3, with an interior rib *j'*, which is adapted to be seated in the groove *i''* of the assembled insulating parts *i*, *k*, *l*; the latter (Figs. 4^a and 5^a) being but partially grooved since they are designed for the 80 spacing or terminal insulators only.

The requisite number of paired springs *e* and coacting terminals *f* being assembled in groups, or otherwise, as indicated in Figs. 3^a and 5, for example, and tightly compressed to insure the retention of the parts in place, the binding strip *j* is positioned about the assembled insulators, springs and terminals, and the ends *j''* thereof are 85 passed through openings cut in frame *a*, and bent inwardly to secure the composite mounting strip in position upon the relay. The wires forming the terminals *f* are then 90 passed through staggered holes bored for their reception in the common actuating strip *m* of fiber or other insulating material, which strip *m* is secured at the ends of the lever arms *c'*. Thus the rounded cylindrical 95 ends of said terminals are held closely adjacent to the staggered ends of their coacting paired springs, as best shown in Fig. 5; the normal tension of the flattened wires 100 serving to maintain the terminals out of contact, and the armatures in their normal 105 positions, at a short distance from the cores of their respective electro-magnets. Upon the excitation of said magnets, the armatures will be instantly attracted, thereby 110 raising their extended ends *c'*, the attached 115 insulating strip *m*, and respectively engaging the round wire terminals *f* between their 120 paired springs *e*; the contact relation thereof being shown by the springs and terminals of Fig. 4. By staggering the divergent ends 125 of the springs in horizontal planes, there is afforded no opportunity for short-circuiting these closely-assembled members, while all are accessible for inspection, and adjustment in the relay as mounted for giving 130 service. Since the paired springs terminate one side of the circuit, while the wire terminal forms the other side of said circuit within the relay, series contacts are avoided and an efficient rubbing contact with relatively light pressure, is insured for the terminal, between said springs. This member, moreover, is easily entered between the paired springs, while the tension of the flattened wire, tends to separate the terminal from between its spring contacts, and the 135

concerted action of said terminals makes the relay self-restoring. The tension of these spring terminals is regulated by the length of the flattened rear portion, as well as the 5 gage or thickness to which said wires are flattened. It will be seen that the rearwardly roughened springs and terminals are securely held within the composite mounting strip, which in turn, is rigidly bound 10 upon the relay by the inclosing strap; thereby affording a cheap and efficient assemblage for these parts. Instead of using the separate fiber insulators, however, I also mount the springs and terminals in suitably 15 spaced relation, within a jig and embed the parts within an insulating cement *n*, which takes the place of the fiber blocks and mounts the springs in equally close relation as shown in Figs. 4 and 7^b. A cement of 20 gum-arabic, lava-dust and plaster-Paris may be used.

The contact-breaking relay of Figs. 1 and 4 is structurally the same as the one already described, except as to those details which 25 adapt it for opening a plurality of normally closed circuits, and the provision of cement-insulated springs and terminals. In this relay, the strip *m* is mounted within a rectangular yoke *o'* which is actuated by the 30 relay armatures to raise said strip against the tension of the terminals *f* and open the several controlled circuits at the paired spring contacts *e*. These terminals and springs are positioned upon an extension *a'* 35 of the frame which mounts them in a plane below the electromagnets.

In Figs. 1^a, 2^a and 3^a, a five-unit mounting of relay contacts is provided, controllable by a corresponding number of the electro- 40 magnets *b*. The springs and associated terminals are mounted in groups of four co-acting sets, each controllable by its own armature. Otherwise, the construction is 45 identical with the relay of Figs. 2 and 5 heretofore described.

The modified type shown in Fig. 4^b is a contact-making relay, utilizing the mounting of springs, and terminals previously explained, but a single armature *c''* is provided for actuation by the elongated electromagnet *o*. This is provided with extension pole-pieces *p*, fitted upon the core of said magnet and respectively facing the extremities of the armature *c''*. Screw-bolts *q* of 55 brass having their heads tapped to receive the screws *r* extending through frame *u*, are attached to the extension poles for securing the electromagnet in position upon the relay. This type of relay develops a much higher 60 efficiency for a given current consumption, than do the relays previously described, and moreover, it is cheaper to construct, than are the others, which recommends it for most of the applications, to automatic or 65 semi-automatic telephony. The extension

poles insure short air-gaps between their outer faces, and the armature lying parallel with the core of the electromagnet, while the diamagnetic mounting compels the closure of the magnetic lines substantially 70 through said armature, rather than through the frame.

The novel means for mounting the contact springs, provided in the inclosing strap having its ends clenched or suitably secured 75 upon the opposite side of the frame, affords a simple and extremely cheap construction. It will be observed that the contact springs and the flattened portions of the terminals are mounted in different planes, at right 80 angles to each other within the insulation. These terminals serve to lock the separate insulating-parts against vertical movement, because of their engagement within the two opposing grooves between each adjacent 85 pair of insulating parts. Thus the usual intermediate fastening-means, whenever a plurality of contact springs and insulating parts are assembled in prior constructions, has been obviated by the interlocking features 90 of the present type of mounting. Greater rigidity is insured by using a ribbed inclosing strap for the assembled-parts.

The terminals *f* preferably are made of phosphor-bronze wire cut to lengths corresponding with the contact springs. The flattened rear portions of these terminals, afford soldering contacts for the wires, while the portions thereof intermediate of the insulating mountings of said terminals, 100 constitute springs for restoring the armature, thus making the same self-restoring. Since the actuating insulator strip for the terminals is disposed rearwardly of the contact-making ends of the springs and terminals, these parts are accessible for inspection and adjustment, while the relay is connected for giving service.

Having now described several types of relay constructed in accordance with the 110 principles of my invention, I claim as new and desire to secure by these Letters Patent, the following:

1. In a relay device, the combination with a plurality of contact springs mounted in closely adjacent vertical planes, of a plurality of spacing insulators respectively positioned therebetween, an inclosing binding-strap provided with attaching terminals mounting the same, a mounting-frame to which said strap is terminally secured, an electromagnet, its movable armature and means associated with said armature for altering the electrical relation of said 115 springs, substantially as set forth.
2. In a multiple contact relay, the combination with an electromagnet and its actuating armature, of a plurality of springs mounted closely adjacent and upon edge in horizontal planes, whereby the contact-mak- 120 125 130

ing ends thereof are in staggered relation along said horizontal planes, and means controllable by the armature for altering the electrical relation of said springs, substantially as set forth.

3. In a relay device, the combination with an electromagnet and its actuating armature, of paired contact springs having divergent ends adapted to form one circuit terminal, a second circuit terminal having a rounded or cylindrical contact-making portion and a flattened springlike body-portion, a stationary insulating mounting therefor, and means controllable by the armature for engaging and disengaging the second terminal intermediate of the paired contact springs, substantially as set forth.

4. In a multiple contact relay device, the combination with a plurality of rectangular paired contact springs having divergent ends; the said ends being disposed in staggered relation, coacting terminals positioned adjacent to said ends and adapted respectively to be actuated therebetween, an electromagnet, its armature and means governed by the armature for engaging and disengaging the terminals between said contact springs, substantially as set forth.

5. In a relay device of the class described, the combination with an electro-magnet and its actuating armature, of a plurality of paired contact springs mounted on edge in a horizontal plane, a plurality of contact terminals mounted adjacent to the contact-making portions of the paired springs; said portions and terminals being disposed in staggered relation in a plurality of horizontal planes, and means controllable by the armature for engaging and disengaging the respective terminals intermediate of the paired contact springs, substantially as set forth.

6. In a relay device of the class described, the combination with a plurality of contact springs and their associated terminals, of a plurality of interposed spacing insulators, slotted upon their sides to accommodate said springs and terminals, and along their tops to accommodate a binding-strap, said binding-strap inclosing the assembled springs and insulators; the same having a ribbed portion to engage the top slots formed in said insulators, and adapted to hold them in their assembled relation against displacement, an electro-magnet, its actuating armature, and means controllable thereby for altering the electrical condition of the springs and terminals, substantially as set forth.

60 7. In a relay device, the combination with an electro-magnet and its actuating armature, of a plurality of contact springs, an associated terminal comprising a wire flattened and rendered spring-like throughout a portion of its length, whose rounded por-

tion is adapted to be entered between the contact springs, an insulating mounting for the springs and terminal at a distance from their contact making portions, and means controllable by the armature for engaging and disengaging the wire between said springs by flexing its flattened portion, substantially as set forth.

8. In a relay device, the combination with an electro-magnet and its actuating armature, of a plurality of contact-making members having their mounting portions roughened, a plurality of spacing insulators shaped to accommodate and engage the roughened portions of said members, an assembling member adapted to compress and hold the parts firmly against displacement, attaching parts therefor, and means controllable by the armature, for altering the electrical relation of said contact-making members, substantially as set forth.

9. In a relay device of the class described, the combination with a plurality of paired contact springs, substantially rectangular in shape and having divergent ends arranged in staggered relation along horizontal planes, of a plurality of coacting wire contact terminals, an insulating member holding the contact making ends thereof in staggered relation, an electro-magnet, its armature, and means controllable by said armature for engaging and disengaging said terminals intermediate of the respective paired contact springs, substantially as set forth.

10. In a relay of the class described, the combination with a plurality of paired contact springs, of a plurality of coacting wire terminals adapted to be respectively flexed into engagement therewith, a common insulating member mounting said terminals adjacent to their contact-making portions, and adapted to hold them in relative position with respect to the springs, an electro-magnet and its bell crank armature; the free arm thereof lying parallel with said terminals and engaged by said insulating member, whereby said terminals are actuated and the armature is restored by the tension thereof, substantially as set forth.

11. In an electrical contact-making device, the combination with an insulating mounting, of a plurality of contact springs mounted thereon closely adjacent upon edge along a horizontal plane, a plurality of coacting spring contacts mounted flatwise in a horizontal plane closely adjacent thereto, and means for altering the electrical relation of said contacts, substantially as set forth.

12. In a device of the class described, the combination with a plurality of insulating parts, of a plurality of contact springs and spring contacts mounted between said insulating parts; the insulated parts being grooved or channeled to mount one set of

contacts with the bodies thereof positioned in planes at right angles to the other, intermediate of the adjacent insulating parts, a binding strap inclosing said insulating parts 5 and contacts for securing them closely together against displacement, substantially as set forth.

13. In a relay device, the combination with a frame of an electro-magnet and its 10 armature mounted thereon, a plurality of contact-making springs controlled by the armature, a plurality of insulating parts mounting said springs therebetween, and an inclosing strap firmly securing said springs 15 and insulating parts upon the frame; the ends of said strap being passed through the frame and secured upon the opposite side from the springs, substantially as set forth.

14. In a relay device, the combination 20 with a frame of a plurality of contact springs insulatingly mounted upon said frame, an electro-magnet mounted upon the frame at right angles to said springs at a distance from their free ends, an armature 25 controlling said contact springs positioned parallel with said electro-magnet also controlling the contact springs, and extension pole pieces extending from either end of the electro-magnet to insure a small air-gap adjacent to the ends of the armature, substantially as set forth.

15. In a multiple contact relay, the combination with a frame, of a plurality of contact springs thereon, a straight-core electro- 35 magnet disposed at right angles to said springs at a distance from their free ends, a bell crank armature having one arm extending in a plane adjacent to said springs and controlling their electrical relations, and the 40 other arm disposed parallel to said electro-magnet, and extension pole pieces bridging substantially the distance between the magnet-core and the ends of the armature, substantially as set forth.

45 16. In a multiple contact relay, the combination with a plurality of contact springs, of a plurality of co-acting terminals positioned substantially parallel therewith and adapted to be flexed into contact with said 50 springs adjacent to their respective ends, a common insulating strip inclosing and movably mounting said terminals rearwardly of their plane of contact with said springs, an electro-magnet and its armature connected 55 with said insulating strip and adapted to actuate the terminals into and out of engagement with the springs, substantially as set forth.

17. In a multiple contact relay, the combination with a plurality of contact springs, 60 rectangular in outline, of a plurality of co-acting terminals, an insulating mounting rearwardly maintaining the same in two adjacent planes, a common insulating strip for 65 the free ends of the terminals positioned

rearwardly of the rectangular ends of the springs, an electro-magnet and its armature connected with said strip for the actuation of the terminals into and out of engagement with the springs, substantially as set forth. 70

18. In an electrical contact-making device, the combination with a plurality of separate insulating parts grooved in two different planes, of a plurality of flattened spring contacts respectively mounted between said insulating parts and interlocking the same, an inclosing binding strap, and means for altering the electrical relation of the spring contacts, substantially as set forth. 75

19. In a multiple contact relay, the combination with a plurality of contact springs arranged in paired relation and upon edge, of a plurality of co-acting contact terminals positioned in a plane substantially parallel 80 therewith and adapted respectively to be flexed vertically into engagement between the paired contact springs, whereby the latter are horizontally flexed, and electro-magnetic means for actuating said contact terminals, substantially as set forth. 85

20. In a multiple contact relay, the combination with a plurality of contact springs, rectangular in outline, and presenting opposed or paired engaging terminals, of a 90 plurality of springlike contact terminals positioned respectively to be engaged between said terminals, whereby contact may be established between springs respectively flexed in planes at right angles to each other, and 95 electro-magnetic means for actuating the contact parts into and out of engagement, substantially as set forth. 100

21. In a multiple contact relay, the combination with a frame, of a plurality of contact springs insulatingly mounted thereon, a single core electro-magnet mounted upon the frame at a distance from the free ends of said springs and at right angles thereto, a bell-crank armature for said magnet having 105 one arm extending substantially to the free ends of the springs and the other arm disposed parallel to the electro-magnet, extension pole pieces bridging substantially the 110 distance between the magnet core and the actuated end of the armature, and means associated with the other end of the armature for actuating the contact springs, substantially as set forth. 115

22. In a relay device, the combination 120 with an electro-magnet and its angular armature, of a supporting frame upon which said armature is rearwardly fulcrumed, an insulating mounting rearwardly positioned upon the frame adjacent to the axis of said 125 armature, sets of co-acting contact-making members overlying said armature and mounted by said insulation substantially parallel to the angularly extended end, and an insulating member positioned rearwardly 130

of the engaging portions of said contact making members and supported by the extremity of the armature, whereby the contact making members are flexed into and out of engagement with their free ends extending forwardly beyond the armature, substantially as set forth.

In testimony whereof I do now affix my signature in presence of two witnesses.

GARRISON BABCOCK.
